(57) CLAIM

The ornamental design for a tow handle, as shown and described.

DESCRIPTION

FIG. 1 is a perspective view of a tow handle showing my new design.

FIG. 2 is a top plan view thereof, the bottom plan view being a mirror image thereto.

FIG. 3 is a right side elevational view thereof, the left side elevational view being a mirror image thereto.

FIG. 4 is a forward end elevational view thereof; and, FIG. 5 is a rearward end elevational view thereof.

The broken lines in the drawings are for illustrative purposes only and do not form part of the claimed design.
